WIRE HANDLING DEVICE

Martin J. Hohner, Wheatfield, Ind.

Application April 14, 1938, Serial No. 202,103

2 Claims. (Cl. 242—94)

The present invention relates to new and useful improvements in devices for handling wire, particularly barbed wire, and has for one of its important objects to provide, in a manner as hereinafter set forth, a device of this character embodying a novel construction through the medium of which a spool of wire may be rapidly unwound by one man with a minimum of labor.

Another very important object of the invention is to provide a wire handling device of the aforementioned character embodying novel means for maintaining the spool and the wire thereon in proper condition as said wire is unwound and which may be used with facility under various conditions, such as on the side of a hill, in high grass, or on uneven ground, etc.

Other objects of the invention are to provide a wire handling device of the character set forth which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a plan view of an embodiment of the invention.

Figure 2 is a view in side elevation thereof.

Figure 3 is a view partially in plan and partially in horizontal section, showing one end portion of the invention.

Figure 4 is a detail view in elevation of one of the removable discs.

Figure 5 is a view in side elevation of one end portion of the device with the discs omitted.

Figure 6 is a perspective view of an end portion of the frame.

Referring now to the drawings in detail, it will be seen that the embodiment of the invention which has been illustrated comprises a substantially U-shaped tubular metallic frame which is designated generally by the reference numeral 1. The frame 1 includes a handle 2 and spaced, parallel legs 3, said legs 3 having one end connected to the ends of said handle 2 by elbows 4.

The elements constituting the frame 1 may be of any suitable diameter.

The reference numeral 5 designates a tubular metallic axle which is mounted transversely on the free end of one of the frame legs 3 through the medium of an elbow 6. Threadedly mounted

on one end portion of the axle 5 is a removable plate 7. Mounted on one end portion of the plate 7 is a threaded shank 8 which is engageable in an opening 9 which is provided therefor in the flattened end portion 10 of the adjacent leg 3. A nut 11 is threaded on the shank 8 for removably securing the plate 7 on the adjacent leg 3 of the frame 1.

Journalled on the end portions of the axle 5 are removable metallic discs 12 which may be of any suitable thickness and diameter. Secured to one side of the discs 12 are bearing rings 13 of suitable metal. Of course, the rings 13 increase the area of the bearing surfaces of the discs 12 on the axle 5. In Figs. 1 and 2 of the drawings, the reference numeral 14 designates generally a spool of barbed wire rotatably mounted on the axle 5 between the side discs 12.

It is thought that the operation of the device will be readily apparent from a consideration of the foregoing. To mount the spool of wire on the axle 5, the nut 11 is removed and the adjacent leg 3 of the frame 1 is sprung outwardly to disengage it from the element 8. The plate 7 is then unscrewed from the axle 5 and the adjacent disc 12 is removed from said axle. The axle 5 is then inserted through the spool of wire and the elements above referred to are replaced. To permit the insertion of the axle 5 in the spool and also to permit mounting or removing the discs 12, said axle with the elbow 6 may be swung on the leg of the frame 1 on which said elbow 6 is threaded, or the other leg 3, which has been disconnected from the plate 7, may be swung with its elbow 4 on the handle 2. Or, if desired, the construction and arrangement may be such that the axle 5 may be unscrewed from the elbow 6, inserted through the spool of wire and replaced. The plate 7 is of substantially the shape shown to advantage in Fig. 5 of the drawings. As the device with the spool of wire thereon is pulled over the ground by the handle 2 the wire is unwound uniformly, is prevented from loosening or unravelling on the spool and is caused to lie flat on the ground. The discs 12, after a portion of the wire has been unwound, are adapted to roll on the ground and support the spool, thus making for smooth operation and taking the weight off said spool.

It is believed that the many advantages of a wire handling device constructed in accordance with the present invention will be readily understood and although a preferred embodiment of the device is as illustrated and described, it is to be understood that changes in the details of

construction and in the combination and arrangement of parts may be resorted to which will fall within the scope of the invention as claimed.

5. What is claimed is:

1. A wire handling device comprising a substantially U-shaped frame, a transverse axle mounted on one end of one of the legs of the frame and adapted for insertion through a 10 spool of wire, removable discs journaled on the end portions of the axle, and means for detachably connecting one end portion of the axle to the free end portion of the other leg of the frame, said means including a removable plate threadedly 15 mounted on said one end portion of the axle, a threaded shank fixed on said plate and

insertable through said other leg of the frame, and a nut threaded on said shank.

2. A wire handling device comprising a substantially U-shaped frame including a handle and parallel legs on said handle, a transverse axle having one end connected to the free end of one of the legs, removable discs journaled on the end portions of said axle, the free end portion of the other leg being flattened and having an opening therein, a removable plate threadedly 5 mounted on the other end portion of the axle, a threaded shank on the plate engageable in the opening, and a nut threaded on said shank for detachably securing the plate to said other leg 10 of the frame.

MARTIN J. HOHNER.
